Des. 203,142
Patented Dec. 7, 1965

203,142

ELECTRIC TACKER

Norman R. Doherty, 32 Sunset Ave., Farmingdale, N.Y.

Filed Jan. 4, 1965, Ser. No. 83,262

Term of patent 14 years

(Cl. D54—14)

FIG. 2

FIG. 4

FIG. 1

FIG. 5

FIG. 3

FIG. 1 is a side elevational view of an electric tacker showing my new design, the side opposite thereto being similar in appearance;

FIG. 2 is a front elevation as viewed from the right of FIG. 1;

FIG. 3 is a rear elevation as viewed from the left of FIG. 1;

FIG. 4 is a top plan view; and

FIG. 5 is a bottom plan view.

I claim:

The ornamental design for an electric tacker, substantially as shown and described.
